METAL REMOVING MACHINE FOR BALANCING

Fred J. Helwig, Cleveland, Ohio, assignor, by mesne assignments, to Possis Machine Corporation, Minneapolis, Minn., a corporation of Minnesota

Filed Mar. 27, 1967, Ser. No. 6,402

Term of patent 14 years

(Cl. D55—1)

FIG. 5

FIG. 6

FIG. 1 is an isometric view of a metal removing machine for balancing embodying my new design as seen from the front-right corner;

FIG. 2 is a top plan view of the machine of FIG. 1;

FIG. 3 is a front elevation view thereof;

FIG. 4 is a rear elevation view; and

FIGS. 5 and 6 are side elevation views of such machine as viewed from the right and left sides of FIG. 1, respectively.

The dominant features of my new design reside in the portions shown in full lines.

I claim:

The ornamental design for a metal removing machine for balancing, substantially as shown and described.
